UNITED STATES PATENT OFFICE.

CHAPMAN J. ROOT, OF TERRE HAUTE, INDIANA.

DESIGN FOR A BOTTLE.

Application filed November 25, 1921. Serial No. 517,783. Term of patent 14 years.

To all whom it may concern:

Be it known that I, CHAPMAN J. Root, a citizen of the United States, residing at Terre Haute, in the county of Vigo and State of Indiana, have invented a new, original, and ornamental Design for a Bottle, of which the following is a specification, reference being had to the accompanying drawings, forming part thereof.

The accompanying drawings illustrate my invention, Fig. 1 being a side elevation of the bottle in my design and Fig. 2 a transverse section on line 2—2 Fig. 1.

I claim as my invention:

The ornamental design for a bottle, as shown.

In witness whereof, I, CHAPMAN J. Root, have hereunto set my hand at Indianapolis, Indiana, this 22nd day of November, A. D. one thousand nine hundred and twenty-one.

CHAPMAN J. ROOT.
